CARRIER WAVE SYSTEM COMPENSATED
AUTOMATIC GAIN CONTROL

Harold F. Elliott, Palo Alto, Calif.

Application December 19, 1933, Serial No. 703,054

6 Claims. (Cl. 250—20)

My invention relates to carrier wave systems such as are used for communication by telegraphy, telephony, facsimile and television over wire and radio circuits and especially to systems embodying means for automatically controlling the output level at the receiving terminals.

One object of my invention is to extend the range of control of such systems. Another object is to improve the precision of control. Another object is to improve the stability of such systems. Still another object is to improve the quality of reproduction. These and other objectives will be described more fully in the following description and appended claims.

15 Referring to the accompanying drawing in which like numerals of reference indicate similar parts throughout the several views:

Figure 1 is a schematic diagram illustrating one form of my invention;

20 Figure 2 is a circuit diagram of a carrier wave receiving system embodying my invention; and

Figure 3 gives curves showing the results obtained by my invention as compared with previous systems.

25 In the schematic diagram of a carrier wave receiver embodying my invention, as shown in Fig. 1, the incoming carrier waves from wires or radio antenna are applied to the input terminals 1, of a carrier frequency amplifier of one or more stages. By way of illustration, three carrier frequency amplifiers 2, 3 and 4 are shown, but the invention is not in any sense restricted to this number of amplifiers as more or less may be used. The amplified output, appearing at 5, is 30 applied in suitable proportion to a governor 6 which serves to rectify the carrier waves, with or without further amplification and selection, and to deliver governing potentials at 7. A suitable proportion of these potentials is utilized 35 through connections 8 for automatically governing or controlling the gain of amplifiers 2, 3 and 4.

40 This much of the system so far described is similar to systems embodying automatic gain or volume control now in use. The relation between input and output of such systems, when well designed, will be about as shown by curve B in Figure 3. A variation of 60 to 80 decibels in the level of the signals applied to the input terminals 1, is held to a variation of 10 to 20 decibels at the output terminals 5. If it is attempted to hold the output variation within closer limits, the system becomes unstable. Stable governing action can only be attained when there is a material slope in the input-output 45 curve. While such a variation in output is not

objectionable for some purposes, there are other uses where it is desirable to have a much more nearly constant output, and one of the main objectives of my invention is the provision of means which accomplish this and also extend the range of control while maintaining stability and high quality of reproduction.

50 In the form of my invention shown in Figure 1, the desideratum above-mentioned is carried out by a carrier frequency compensator 9, which receives amplified and governed carrier frequency signals from 5 and governing potentials from 7, each in suitable proportion, through connections 10 and 11. Compensator 9 by preference takes the form of a carrier frequency amplifier of one or more stages having provisions for a variation of gain which preferably just compensates for the variations in the level of the governed signals at 5. The output of compensator 9 at terminals 12 is then constant, regardless of variations at terminals 1 or 5. The relation of the input at 1 to the output of the system as a whole at 12 is then as shown in curve A, Figure 3. The output from terminals 12 may be passed to a further amplifier or to a line, or an antenna, or to a demodulator, or utilized in any desired manner. The amplifiers 2, 3 and 4 and compensator 9 should be of the type in which it is possible to vary the gain over a considerable range without introducing objectionable distortion. One way of accomplishing this is to use so-called "multi-mu" electronic amplifier tubes which have a control characteristic free from abrupt changes in curvature and which can be used as controlled carrier frequency amplifiers over wide ranges without introducing objectionable distortion.

55 Before discussing the detailed circuits, it may be well to point out more specifically why the arrangements shown in Figure 1 make it possible to obtain precise control over a wide range, as illustrated by curve A in Figure 3, whereas previous methods have failed either to give satisfactory range or precise control or have introduced serious distortion or have been unstable or had other defects. In the first place, the circuit arrangement of my invention makes it possible to proportion the carrier frequency amplifier and governor so that stability, constancy, freedom from distortion and dependable performance are attained. Secondly the use of a compensator, operating at carrier frequency, after the main carrier frequency amplifier and governor, makes it possible to compensate for and correct the variations in the output of the amplifier and governor without introducing ob- 55

jectionable distortion, or disturbing the stability or constancy of operation of the system. By placing a compensator at this point in the system, and by suitably proportioning it and the potentials applied to it, it is possible to maintain very constant output from the system as a whole with high quality of reproduction, stability, and dependability. Normal variations in tube constants or potentials have little effect upon the 10 operation. There are no critical adjustments and any desired operating characteristics within reason are attainable. Previous methods, on the other hand, have failed to accomplish constant output by a wide margin or have been 15 unstable, or have introduced serious distortion or have been critical of adjustment or have varied in performance with tube and potential changes.

Figure 2 shows detailed circuits of a carrier 20 frequency receiver, such as may be used for radio or wire line reception, embodying my invention. Carrier wave signals applied to the input terminals 13 are amplified in the carrier frequency amplifier tubes 14, 15 and 16, which are 25 preferably of the so-called "multi-mu" or other type permitting a wide range of amplification control without introducing objectionable distortion. The amplifier 14-15-16, may be of the type in which the entire amplification function 30 is carried out at a single carrier frequency, or it may be of the type in which the frequency is converted to a lower or higher periodicity, as is done, for example, in superheterodyne systems. If the latter is used, tube 15 may, if desired, be a frequency converter tube and a suitable heterodyning frequency may be applied in any convenient manner, as, for example, through terminals 17. The transformers between stages and the connections for applying and controlling the various 35 operating potentials may be of any convenient and suitable form. These are not described in detail here since these matters are well understood, and this description may be simplified by confining it to the details that are new and novel.

40 In Figure 2, I have shown the output of the last main carrier frequency amplifier stage 16, as feeding into an output transformer with tuned primary and secondary, 18 and 19 but it will be understood that any other suitable output termination 45 may be employed. A connection 20 leads from a suitable point on secondary 19 to the input of governor 22. Another connection 21 leads from another suitable point on secondary 19 to the input of compensator 24. It will be noted that 50 both governor 22 and compensator 24 are supplied with carrier frequency signals from the output of amplifier 16. Other arrangements may be employed in carrying out the invention but the particular arrangement shown has been 55 found very effective and stable in operation as well as relatively simple in construction.

The governor comprises a carrier frequency amplifier tube 22, and a full wave rectifier 25, which serves to rectify the output of tube 22 and 60 supply direct current governing potentials at potentiometer 26. Any other arrangement supplying suitable governing potentials may be employed, but again, the circuits shown have been found to be both simple and effective in practice.

65 Suitable potentials from potentiometer 26 may be applied through a suitable system of filters and connections 27, to the gain control circuits of amplifiers 14, 15 and 16. Amplifiers 14, 15 and 16 together with governor 22-25 constitute a 70 self-governing amplifier whose output at second-

ary 19 is held within the limits usually obtainable in amplifiers with well designed automatic gain control, as illustrated by curve B in Figure 3.

A suitable proportion of the controlled output from amplifiers 14-15-16 at secondary 19 may be applied through suitable connections 21 to the input of compensator 24. Also a suitable proportion of the governing potentials at 26 may be applied through appropriate filters and connections, as 23, to a gain control electrode or other suitable 10 gain control means, in compensator 24. Compensator 24 should be a "variable mu" electronic tube or other device in which the output may be controlled relative to the input without introducing objectionable distortion, and the applied 15 potentials and control characteristics should be such that the relation of output to input exactly offsets the rising characteristic of the output of the preceding amplifier and governor. In some cases, it may be found advantageous to utilize a 20 special tube at 24 for this purpose. In other cases, very satisfactory results may be obtained by utilizing a standard commercial tube. Very good results were obtained with the system shown in Figure 2, operating as a superheterodyne radio 25 broadcast receiver, by employing standard "multi-mu" tubes at 14, 15, 16, 22 and 24, and a standard full wave rectifier at 25. In this particular receiver, the full rectified potential from 25 was applied to the gain control circuit 27, of tubes 14, 30 15 and 16 and about one-half of this potential was applied to the gain control circuit 23 of compensator tube 24. The initial bias on tubes 14 and 16 was set by rheostat 28 and rheostat 29 was used for the same purpose on compensator 35 tube 24. It was found that the output of compensator 24, could be made very constant over a very wide range of inputs at 13 by suitably adjusting the initial bias at 29 and properly proportioning the control potential taken from 40 potentiometer 26.

While I have shown compensator 24 as comprising a single variable "mu" tube, it will be understood that additional tubes or even entirely different means may be utilized if needed or desired. As already outlined, the output of the compensator 24 may be passed to a further amplifier, or to a wire line, or to a demodulator or utilized in any desired manner. In the broadcast receiver shown in Figure 2, compensator 24 50 is shown as provided with an output transformer having tuned primary and secondary feeding into a full wave diode rectifier 30. The output of the latter is shown feeding into an audio frequency amplifier 32 through a potentiometer 31, with the 55 output of the system appearing as audio frequency signals at terminals 33. Such an arrangement of a radio receiver is very advantageous since the rectifier 30 or other detector operates at a very constant level which can be proportioned 60 and adjusted for the highest quality of reproduction and most effective operation.

Since the audio output of the system is substantially constant, some visual means of indicating when the circuits are tuned to resonance with the 65 incoming carrier is desirable. Such an indicator is shown at 34 in Figure 2. Indicator 34 may comprise any desired or known instrumentality.

It will be apparent that many variations may be made without departing from the spirit of 70 the invention, as defined in the appended claims and that details of wiring, filtering, tuning provisions, etc., may be carried out in an almost infinite variety of ways.

The question may arise as to whether the 75

method may be applied to the compensation of signals at audio frequency and this may be accomplished if the design of the compensator and the proportion of the signals and potentials applied to it are such that the necessary range of control can be accomplished without introducing objectionable distortion. The necessary control range and other essential features are readily obtained when the compensator is operated at carrier frequencies as shown in the accompanying diagrams and this is therefore given as the preferred form of the invention.

With reference to the location of manual means for controlling the absolute output of a system of the type described, such control means should preferably, though not necessarily, follow the compensator 9 in Figure 1 or 24 in Figure 2. If the compensator is followed by a detector and audio amplifier, the manual control may be on either side of the detector or may be in the audio amplifier. If the compensator feeds to a line, the control may be either side of the compensator and may take any suitable form. The preferred location is after the compensator or after the detector.

Having thus described my invention, I claim:

1. A superheterodyne radio receiver comprising a radio frequency amplifier with tuned circuits and a tube having gain control means, a frequency converter having tuned circuits and a tube having gain control means, an intermediate frequency amplifier having tuned circuits and a tube having gain control means, a governor comprising an amplifier and a diode rectifier interconnected by a tuned circuit, a circuit connecting the input of the governor and the output of the intermediate frequency amplifier, a circuit connecting the output of the rectifier and the gain control means in the radio frequency amplifier, frequency converter and intermediate frequency amplifier, an intermediate frequency compensator having input and output circuits and gain control means wherein the gain characteristic inversely and proportionately matches and offsets the input-output characteristic of the radio frequency amplifier-frequency converter-intermediate frequency amplifier and governor combination, a circuit connecting the input circuit of the compensator and the output of the intermediate frequency amplifier, a circuit with potential proportioning means connecting the gain control means of the compensator and the output of the rectifier, a detector with input and output circuits, a circuit connecting the input of the detector with the output of the compensator, an audio amplifier with input and output circuits, a circuit connecting the input to the audio amplifier and the output of the detector and a volume control regulating the input to the audio amplifier.

2. A radio receiver comprising a carrier frequency amplifier having a plurality of multi-mu amplifier tubes, input and output circuits and tuning means, a governor comprising an amplifier followed by a diode rectifier, input and output circuits and tuning means, a resistor with tapping means in the output of the rectifier, a connection between the output of the carrier frequency amplifier and the input of the governor, connections between the resistor and gain control electrodes in the multi-mu tubes, a compensator comprising a tube having a variable gain characteristic which is the complement and inversely proportionate to the input-output characteristic of the carrier frequency amplifier-governor combination, input, output and gain control circuits for the compensator, a connection from the compensator input to the output of the carrier frequency amplifier, a connection from the compensator gain control circuits to the resistor, a detector with input and output circuits, a connection from the detector input to the compensator output, an audio amplifier with input and output circuits, and a circuit including volume control means interconnecting the output of the detector and the input of the audio amplifier.

3. In combination, a main carrier frequency amplifier with input and output circuits and gain control means, a governor comprising a carrier frequency amplifier followed by a diode rectifier with input and output circuits, connections from the input of the governor amplifier to the output of the main carrier frequency amplifier, connections from the rectifier output to the gain control means, a carrier frequency compensator comprising input and output circuits and a variable gain electronic tube having in combination with the potentials applied thereto an input-output characteristic whose slope is inversely proportionate and complementary to the slope of the input-output characteristic of the main carrier frequency amplifier and governor, connections from the compensator input to the main carrier frequency amplifier output, connections from the rectifier output to gain control means in the compensator, a constant level detector connected to the output of the compensator and an audio frequency amplifier connected through a volume control to the output of the detector.

4. A superheterodyne receiver in accordance with claim 1 with the addition of potentially operated tuning indicating means.

5. A radio receiver in accordance with claim 2 with the addition of potentially operated tuning indicating means.

6. The combination as set forth in claim 3 with the addition of resonance indicating means.
